UNITED STATES PATENT OFFICE.

CHARLES R. KEERAN, OF CHICAGO, ILLINOIS, ASSIGNOR, BY MESNE ASSIGNMENTS,
TO AUTOPOINT COMPANY, OF CHICAGO, ILLINOIS, A CORPORATION OF ILLINOIS.

CLIP FOR PENCILS AND THE LIKE.

Application filed May 24, 1924. Serial No. 716,839.

This invention relates to a clip adapted for permanent attachment to a pencil, pen or the like, and for detachable engagement with the pocket flap so as to prevent loss of 5 the article.

An exemplification of this invention in its preferred form is illustrated in the accompanying drawing wherein—

Figure 1 is a side elevation of the clip attached to the body of a pencil or other similar article;

Fig. 2 is a front elevation thereof; and

Fig. 3 is an enlarged transverse section through the clip taken on line 3—3 of Fig. 2.

15 The article shown in the drawing is provided with a body A having a plurality of flat faces, *a*, *b*, *c*, etc. In cross section the article body may be octagonal, as shown, or hexagonal, or otherwise, it being desirable 20 for the purposes of this invention that at least three contiguous flat faces be provided. Upon one of these, designated as *a*, the clip is attached with portions thereof overlying the contiguous faces *b* and *c*.

25 By preference, the present clip comprises a prong 5 normally spring-pressed against the pencil body; at its upper end the prong is curved inwardly as at 6 to unite with a head 7 through which is formed a hole to

30 receive the shank 8 of a screw whose head 9 overlies the clip head. The screw shank is entered into the body of the pencil to effect a threaded connection therewith, as best illustrated in Fig. 3.

35 The clip head, as will be noted best in Figs. 1 and 2, extends from the screw head upwardly to provide a tongue 10 and laterally to provide wings 11 on each side thereof. These wings, as will appear best in Fig.

40 3, are angularly related to the clip head so as to lie snugly against the contiguous faces of the pencil body. In this manner the cor-

ner 12 formed at the juncture of each wing 11 with the head will rest upon the proximate corner 13 of the pencil body. The effect of this construction is to provide a means which not only centers the clip laterally of the body but which prevents oscillation thereof upon the article to which it is attached.

It is preferred that the clip take a form similar to that shown in the drawing with its tongue 10 projecting upwardly so as to provide a means, in association with the screw, for resisting outward pull of the 55 prong when the clip is placed over a pocket flap. Because of the presence of this tongue, as well as of the two wings 11 which center the clip and prevent its rotary movement upon the body, a single screw, rivet, or other attaching medium, will suffice to secure the 60 clip to the article. The form which the screw head may take is, of course, immaterial, it being suggested in Fig. 3, for instance, that its head may be round and partially countersunk in the clip head. Obviously such features may be considerably 65 varied without departing from my invention, and, as defined by the appended claim, should be construed as within its purview 70 and scope.

I claim:—

The combination with a pencil body of polygonal cross section of a clip comprising an attaching head and a spring prong, said head being angularly shaped to correspond to the contour of the pencil body and to overlie and contact with a plurality of faces of said polygonal body, and a single screw 75 for connecting the clip head to the body. 80

Signed at Chicago, Ill., this 19th day of May, 1924.

CHARLES R. KEERAN.
